US00D485659S

(12) **United States Design Patent** (10) Patent No.: **US D485,659 S**
Medoff et al. (45) Date of Patent: **** Jan. 20, 2004**

(54) **PALLET**

(75) Inventors: **Marshall Medoff**, Brookline, MA (US);
Joseph P. McFadden, Fairfield, CT (US)

(73) Assignee: **Xyleco, Inc.**, Brookline, MA (US)

(**) Term: **14 Years**

(21) Appl. No.: **29/178,564**

(22) Filed: **Mar. 4, 2003**

(57) **CLAIM**

The ornamental design for a pallet, as shown and described.

DESCRIPTION

FIG. 1 is a top perspective view of a pallet with a base plate of the invention;

FIG. 2 is a top plan view of the pallet of FIG. 1;

FIG. 3 is a front elevational view of the pallet of FIG. 1, the back elevational view being a mirror image thereof;

FIG. 4 is a side elevational view of the pallet of FIG. 1, the opposite side being a mirror image thereof;

FIG. 5 is a bottom plan view of the pallet of FIG. 1; and, FIG. 6 is an exploded top perspective view of the pallet of FIG. 1.
